STORAGE RACK

Charles D. Burrell, Toledo, Ohio, assignor to
 Libbey-Owens-Ford Glass Company, Toledo,
 Ohio, a Corporation of Ohio

Application November 18, 1930
 Serial No. 496,536

9 Claims. (Cl. 211—41)

The present invention relates to improvements in apparatus for storing relatively large sheets or plates of glass or the like.

An important object of this invention is the provision of a storage rack of simplified and practical design which will accommodate a maximum number of glass sheets or plates and wherein the said sheets or plates are arranged on edge in a vertical position and maintained in spaced relation with respect to one another.

Another object of the invention is the provision of a storage rack of the character above described which will retain the glass sheets or plates in such a manner that they are readily accessible and can be easily and quickly placed therein or removed therefrom without disturbing the remaining sheets so that accidental breakage of the sheets incident to the storing thereof will be reduced to a minimum if not entirely eliminated.

A further object of the invention is the provision of a storage rack of the character above described which will retain the sheets in the desired position in a positive manner and which is of such construction that it will not mar or scratch the sheets during their insertion therein or removal therefrom.

Other objects and advantages of the invention will become more apparent during the course of the following description when taken in connection with the accompanying drawings.

In the drawings forming a part of this application and wherein like numerals are employed to designate like parts throughout the same,

Fig. 1 is a vertical longitudinal section through a storage rack constructed in accordance with the present invention, one of the sheet retaining frames being shown in elevation.

Fig. 2 is a section taken substantially on line 2—2 of Fig. 1.

Fig. 3 is a section taken substantially on line 3—3 of Fig. 1.

Fig. 4 is a section taken substantially on line 4—4 of Fig. 1.

Fig. 5 is a section taken substantially on line 5—5 of Fig. 1.

Fig. 6 is a section taken substantially on line 6—6 of Fig. 1, and

Fig. 7 is a section taken substantially on line 7—7 of Fig. 1.

The storage rack provided by the present invention includes a base or foundation 10 upon which is supported the flooring 11, said flooring consisting, as best shown in Fig. 2, of a plurality of longitudinally extending wooden strips positioned side by side in abutting relation with

respect to one another and being provided in their upper surfaces with a plurality of spaced longitudinally extending parallel grooves 12 which are adapted to receive therein the lower edges of the glass sheets or plates 13 to be stored. The upper portions of the sheets 13 are adapted to be received between adjacent vertical retaining frames 14 mounted above the base 10 and being spaced from one another a distance substantially equal to the width of the grooves 12 so that there is provided between the frames a space which is in substantial vertical alignment with the said grooves and into which the upper ends of the glass sheets may be slid. The grooves 12 are preferably coated with a suitable floor wax in order to facilitate the sliding of the glass sheets therein.

Inasmuch as all of the retaining frames 14 are of the same construction, a detail description of only one will be given. As best illustrated in Fig. 1, each retaining frame consists of the upper and lower longitudinally extending wooden strips 15 and 16 and a similar intermediate strip 17. These longitudinally extending strips are connected together adjacent their opposite ends and also intermediate their ends by the substantially vertical wooden strips 18. Of course, while only three longitudinally extending strips and four vertical connecting strips have been shown, a greater or a less number can be used as desired.

Each of the substantially vertical strips 18 has a dovetail connection with the upper and lower longitudinally extending strips 15 and 16 as indicated at 19 in Fig. 4, and the overlapping portions of the said strips are preferably glued together and then further secured by means of wooden pins 20. The vertical strips 18 do not have a dovetail connection with the intermediate longitudinal strip 17 but instead, the overlapping portions of the said vertical strips 18 and intermediate longitudinal strip 17 are each cut away approximately one-half in thickness as shown at 21 in Fig. 5 so that, when fitted together, the surfaces of the vertical strips and longitudinal strip will be flush with one another. These overlapping portions are also preferably glued together and passing therethrough are wooden securing pins 22. By entirely eliminating the use of metal nails and screws in the construction of frame 14, all danger of the sheets being scratched or marred by the said frames during the insertion thereof within the rack or removal therefrom will be avoided. The opposite side edges of the vertical strips 18 may also be beveled as at 23 (Fig. 6) to facilitate the insertion of the glass sheets between the retaining frames.

The retaining frames 14 are hung from the supporting I-beams 24 and 25 provided adjacent the front and rear ends respectively of the said frames and extending transversely thereof. Carried by each of these I-beams are a plurality of inverted substantially T-shaped elements 26, each adapted to carry two of the retaining frames 14. Each of the inverted T-shape elements 26 comprises a vertical threaded stem 27 extending upwardly through the corresponding I-beam 24 or 25 and having threaded upon its upper end a nut 28. Formed at the lower end of the stem 27 is the horizontal cross piece 29 having its opposite ends up-turned to provide the vertical portions 30, the cross piece 29 and end portions 30 fitting around the top strips 15 of two adjacent retaining frames. In other words, one frame is adapted to be carried by the supporting element 26 at each side of the stem 27, the longitudinally extending top strip 15 of the frame resting upon the cross piece 29 and being held thereupon by the respective up-turned end portion 30. The frame carrying elements 26 carried by each I-beam 24 and 25 are arranged in staggered relation with respect to one another as best shown in Fig. 3, one element being disposed at one side of the I-beam and the next member at the opposite side thereof. The frames are maintained in spaced relation by the stems 27 and up-turned end portions 30 of the hanger elements 26.

The substantially vertically disposed strips 18 are preferably flexible so that the lower portions of the frames may be swung laterally to one side or the other, if desired, to facilitate the insertion of the glass sheets or plates within the rack. In other words, the lateral swinging of the frames is accomplished due to the flexibility of the vertical strips and not to any swinging connection between the retaining frames and the supporting beams 24 and 25.

Positioned at the rear of the storage rack and extending transversely of the retaining frames 14 are the two longitudinally extending horizontal wooden members 31 and 32 positioned opposite the horizontal strips 16 and 17 respectively of the said frames. These members 31 and 32 are adapted to act as stops to limit the rearward movement of the glass sheets as they are slid into the rack and, in addition, preferably serve to maintain certain of the frames in a more rigid position. In other words, the horizontal strips 16 and 17 of certain of the retaining frames 14 extend beyond the strips of the remaining frames, as indicated at 33 in Fig. 7, and these projecting portions are received within slots 34 in said members. If desired, suitable felt strips or the like 35 can be secured to the inner faces of the members 31 and 32, against which the rear vertical edges of the glass sheets are adapted to abut.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In a storage rack for glass sheets or the like, means for supporting the sheets in a vertical position and for preventing lateral movement of the lower edges thereof, vertically disposed retaining frames mounted above said supporting means and adapted to receive the upper edges of the sheets therebetween, each retaining frame consisting of a plurality of horizontally arranged

strips and a plurality of substantially vertical strips connecting said horizontal strips and means for suspending said frames from the upper ends thereof.

2. In a storage rack for glass sheets or the like, means for supporting the sheets in a vertical position and for preventing lateral movement of the lower edges thereof, vertically disposed retaining frames mounted above said supporting means and adapted to receive the upper edges of the sheets therebetween, each retaining frame consisting of a plurality of horizontally arranged strips and a plurality of substantially vertical strips connecting said horizontal strips, said substantially vertical strips being flexible so that the lower portions of the frames can be swung laterally relative to one another, and means for suspending the frames from the upper ends thereof, the said frames being restrained against lateral movement at the upper ends thereof only. 95

3. In a storage rack for glass sheets or the like, means for supporting the sheets in a vertical position and having grooves for receiving the lower edges of the said sheets therein, vertically disposed retaining frames mounted above said supporting means and adapted to receive the upper edges of the sheets therebetween, each retaining frame consisting of a plurality of horizontally arranged strips and a plurality of substantially vertical strips connecting said horizontal strips, and 105 means for suspending said frames from the upper ends thereof

4. In a storage rack for glass sheets or the like, means for supporting the sheets in a vertical position and having grooves for receiving the lower edges of the said sheets therein, vertically disposed retaining frames mounted above said supporting means and adapted to receive the upper edges of the sheets therebetween, each retaining frame consisting of a plurality of horizontally arranged strips and a plurality of substantially vertical strips connecting said horizontal strips, said substantially vertical strips being flexible so that the lower portions of the frames can be swung laterally relative to one another, and means for suspending the frames from the upper ends thereof, the said frames being restrained against lateral movement at the upper ends thereof only. 115

5. In a storage rack for glass sheets or the like, means for supporting the sheets in a vertical position and having grooves for receiving the lower edges of the said sheets therein, vertically disposed retaining frames mounted above said supporting means and being spaced from one another to receive the upper edges of the glass sheets therebetween, and means for suspending said frames from the upper ends thereof, said last mentioned means also acting to maintain the frames spaced from one another so that the spaces therebetween are in substantial vertical alignment with the grooves in said supporting means. 125

6. In a storage rack for glass sheets or the like, means for supporting the sheets in a vertical position and for preventing lateral movement of the lower edges thereof, vertically disposed retaining frames mounted above said supporting means and being spaced from one another to receive the upper edges of the glass sheets therebetween, and a horizontal stop member extending transversely 145 of the frames at the rear end of the storage rack, certain of the frames having means engageable with the stop member to maintain said frames in a more rigid position.

7. In a storage rack for glass sheets or the like, 150

- means for supporting the sheets in a vertical position and for preventing lateral movement of the lower edges thereof, vertically disposed retaining frames mounted above said supporting means and 5 being spaced from one another to receive the upper edges of the glass sheets therebetween, and a horizontal stop member extending transversely of the frames at the rear end of the storage rack, certain of the frames having projections received 10 within slots in said stop member to maintain said frames in a rigid position.
8. In a storage rack for glass sheets or the like, means for supporting the sheets in a vertical position and for preventing lateral movement of the lower edges thereof, vertically disposed retaining frames mounted above said supporting means and 15 adapted to receive the upper edges of the sheets therebetween, means for securing the frames in position including horizontal supporting members 20
